UNITED STATES PATENT OFFICE.

WILLIAM F. KLEIN, OF ST. LOUIS, MISSOURI.

WINDOW-CASEMENT CONTROL.

Application filed December 23, 1925. Serial No. 77,274.

My invention relates to controls for window sashes and particularly to that class of sashes that are hinged on one side and held in any desired position by means of 5 an adjustable fastener.

The object of my invention is to provide a window casement control that is positive in operation and automatically locks the window at any point desired between the 10 closed position and 90 deg. open.

Another object of my invention is to provide a window casement control that can be used either on top of the window sill or beneath it without leaving an opening from 15 the interior to the exterior of the house.

Other and further objects and advantages of my invention will be apparent from the description, claims and drawings, in which:

Fig. 1 is a plan view of a window partly 20 broken away, showing my device in operative position.

Fig. 2 is a vertical cross-section on the line 2—2 in Fig. 1.

While quite a number of casement controls are now in use, all are subject to the 25 following objections:

Even the most popular controls must be installed upon the top side of the window sill, so that they not only are exposed to 30 view and must, therefore, be highly finished, but they interfere with dusting and cleaning the window sill.

Another objection common to the controls now in use is that they do not automatically 35 lock at any desired point.

A still further objection is that those now in use require an additional lock to secure the sash when the window is closed.

To obviate these disadvantages and to 40 overcome the objections above set forth, I have devised a simple, compact, cheaply constructed and highly efficient window control that automatically holds the window in any position when released, and one that 45 can be inserted through the apron of the window or on top of the sill with equal success.

My improved casement control comprises 50 two movable members 1 and 2, pivotally connected at 3 to form a toggle joint. The opposite end 4 of the member 1 is pivotally joined to a bracket 5, which in turn is securely attached to the lower edge of the sash 6, while the opposite end 7 of the 55 member 2 is pivotally joined by means of a pivot bracket 8 to the sill 9, or the finish 10.

The member 2 is slotted at 11 and articulates by means of the pin 12 inserted through the slot 11 and held in place by the reciprocable barrel 13, having its opposite end 14 screw-threaded internally and adapted to be engaged by the worm 15, said worm being held against longitudinal movement by means of an escutcheon 16 rigidly affixed to the apron 17. A crankarm 18 is rigidly 65 attached to the worm 15.

It is obvious that when the crankarm 18 is rotated in one direction, it will cause the barrel 13 to move outwardly, rotating the arm 2 about its pivotal point 7, which in 70 turn will transmit force through the member 1 causing the toggle joint to approach a straight line, thereby holding the casement 19 in any desired position rotating it about the hinge 20.

It is likewise obvious that a reverse movement of the casement will take place when the crankarm is rotated in the opposite direction. It is, also, apparent that the casement 19 can be firmly held in any position 80 from a closed one to an open one at 90 degrees; hence, when the casement is entirely closed, it is automatically locked, thus saving the expense and necessity of having an additional fastener.

A metal escutcheon 21 may be used to guide the barrel 13, or a small opening can be made through the stool 22 to serve the same purpose.

Having fully described my invention and 90 its method of operation, what I claim as new and useful and desire to secure by Letters Patent is:—

A window casement control, of the class described, comprising a horizontally reciprocable member internally screw-threaded at its inner end adapted to be reciprocated by a rotatable member fixed against longitudinal movement and having its outer end externally screw-threaded adapted to engage the screw-threaded portion of the said horizontally reciprocable member, a crank attached to the inner end of said rotatable member by which said rotatable member may be rotated, a link bar pivotally attached to a window sill and adapted to be rotated through approximately 90 degrees, said pivot joint being located at a rightangle to the longitudinal axis of the said reciprocable member at a sufficient distance therefrom to permit the reciprocable member to be reciprocated without coming in contact 100 105 110 115

with said pivotal joint, said link bar being longitudinally slotted through approximately one-half of its length nearest the said pivot joint and adapted to be slidably engaged by a pin rigidly fixed in the outer end of said reciprocable member, the said link bar being hingedly attached to a second link bar at its outer end, the said second link bar being adapted to be hingedly attached to a hinged member adapted to be attached to a window casement, so that

when the said crank is rotated in one direction, the window casement will be caused to close, and when the crank is rotated in the opposite direction, the window casement will be caused to open, and may be fixedly held at any desired point between fully open and a closed position. 15

In witness whereof I have hereunto affixed my signature this 18th day of December, 1925. 20

WILLIAM F. KLEIN.
